UNITED STATES PATENT OFFICE.

CHARLES E. DUGGAN, OF DETROIT, MICHIGAN.

LOCK.

No. 800,140.

Specification of Letters Patent.

Patented Sept. 26, 1905.

Application filed October 19, 1904. Serial No. 229,114.

To all whom it may concern:

Be it known that I, CHARLES E. DUGGAN, a citizen of the United States of America, residing at Detroit, in the county of Wayne and 5 State of Michigan, have invented certain new and useful Improvements in Locks, of which the following is a specification, reference being had thereto to the accompanying drawings.

This invention relates to a combined fastening and umbrella-holder for suit-cases, trunks, and similarly-constructed receptacles, having two hinge-connected parts to which this fastening may be secured to lock the same together; and its object is to provide a simple 15 and inexpensive fastening having means combined therewith for engaging and holding an umbrella or similar article and also to provide the same with locking means and with certain other new and useful features, all as 20 hereinafter more fully described, reference being had to the accompanying drawings, in which—

Figure 1 is a plan view of a device embodying the invention with the top of the casing 25 broken away to show the construction; Fig. 2, a central longitudinal section of the same. Fig. 3 is a plan view of a device embodying a modified construction, and Fig. 4 a side elevation of the same.

As shown in the drawings, 1 is the base-plate, adapted to be secured to the body of the suit-case or other receptacle, with its forward 30 end coinciding with the edge of the body engaged by the cover, to which cover the catch-plate 2 is secured, and on the base-plate is a casing 3, extending to the forward end of said plate and provided with an opening in its forward end to receive a tapered guide-lug 4 on the catch-plate and center the cover.

5 is a rectangular-shaped loop or hasp pivoted on the casing by providing openings in the side walls of said casing near the base-plate, through which the cross-bar 6 of said hasp extends, the side bars extending parallel with and outside of said side walls and beyond the end of the casing where they are connected, forming a loop to receive the upwardly-projecting lug 7 on the catch-plate.

A loop 8, similar in form to the hasp 5 and 50 having a cross-bar 9, similar to the cross-bar 6, is pivoted to the casing by the engagement of said bar with openings in the sides of the

casing at a short distance from the openings for the bar 6, and at its free end said loop is provided with an integral upwardly-curved 55 finger portion 10 to receive beneath it an umbrella or any similar article.

The hasp and holding-finger are normally held in the position shown in the drawings, the hasp in engagement with its catch-plate 60 and the finger with its base-plate by springs 11, one adjacent to each side wall of the casing within the same and engaging the top of the casing at their ends. Each of the cross-bars 6 and 9 is provided with a lug 12, extending 65 from said bar in the plane of the side bars of the loops, and the springs normally engage the upper side of said lugs, thus exerting a force thereon to hold the hasp and holding-finger in their normal positions, the lugs on 70 each bar extending only part way across the casing, so that but one spring is engaged by it, and thus the hasp is held by its spring independently of the finger.

To lock the hasp and holding-finger in their 75 normal positions, so that the case cannot be opened or the finger lifted to release the article held thereby, a stud 13 is pivotally secured to the base-plate 1 within the casing between the cross-bars, and extending upward between 80 the springs to near the top of the casing is provided with arms 14, extending laterally from opposite sides thereof, so that when said stud is turned by a key inserted through an opening 15 in the top of the casing and engaged with the squared end 16 of the stud said arms will be extended over the cross-bars so close to the upper sides of the lugs thereon that the hasp and holding-finger are prevented from being raised by the engagement 85 of the lugs with said arms. The hasp and holding-finger are released by turning the stud until its arms extend parallel with the cross-bars and between the same, thus permitting the lugs to turn to a vertical position 90 against the action of the springs thereon.

The construction shown in Figs. 3 and 4 is much cheaper to manufacture than that shown in Figs. 1 and 2, as it is formed of sheet metal and is very simple. The base-plate 17 100 is formed from a sheet of metal with side portions 18 forming the side walls of a casing, bent up to form bearings for the hasp 19, which is also formed from a sheet of metal

with downwardly-turned ears 20 at its sides, by means of which it is pivoted to the said walls 18 and with an opening 21 to receive the lug on the catch-plate 2. A downwardly- turned portion on the pivoted end of the hasp adjacent to one of the walls 18 forms a lug 22 to engage the middle of an upwardly-curved spring 23, the ends of which engage the base- plate, and as the said lug is located at one side 5 of the pivot of the hasp and the body of the hasp at the other side the spring will normally exert a force to hold the hasp in engagement with its catch. A curved holding- finger 24, also formed of sheet metal, is similarly pivoted to the walls 18 by being provided with ears 20 and is also provided with a downwardly-turned lug 22, adjacent to the other wall 18, to engage a spring 23, which acts thereon to normally hold the finger in 10 contact with the base-plate.

The advantages of having simple and efficient means whereby an umbrella or similar article may be readily fastened to the suitcase are obvious, as is also the advantage of 15 having the same combined with a fastening for the ears in a simple and efficient manner and forming a part of said fastening, so that it will not look cumbersome or be in the way. By providing means for locking the hasp the 20 ordinary center lock on a suit-case may be dispensed with and at the same time the holding-finger is locked to prevent the umbrella from being stolen or accidentally lost.

Having thus fully described my invention, 25 what I claim is—

1. The combination with a metal fastening for a suit-case or similar receptacle consisting of parts adapted to be permanently secured to the receptacle and to engage each other to 30 hold the receptacle closed, of means attached to and forming a part of said fastening for engaging and holding an umbrella or other article.

2. The combination of means pivotally attached to a suit-case or similar receptacle for engaging and holding an umbrella or other article, and means for normally holding said means turned into engagement with the article to secure the same to the receptacle. 45

3. The combination with a fastening for a suit-case or similar receptacle adapted to be permanently secured thereto to hold the same closed, of means pivotally attached to the fastening and adapted to be turned thereon to 50 engage and hold an umbrella or similar article.

4. The combination with a fastening for suit-cases, &c., of a holding-finger pivotally attached to said fastening and means for normally holding said finger in engagement with an umbrella or similar article. 55

5. The combination with a fastening having a base-plate of a holding-finger pivotally at-

tached at one end to said plate and a spring to force said finger into engagement with an article to hold the same. 65

6. The combination of a fastening for a suitcase or similar receptacle adapted to be permanently secured thereto to hold the same closed, means carried by said fastening for engaging and holding an umbrella or other article, and a key-operated lock to lock said fastening and said means to prevent the opening of the receptacle and the removal of the article from the holding means. 75

7. The combination with a hasp-fastening for suit-cases and similar receptacles, of a finger pivotally attached to said fastening at one end, and a spring engaging the hasp of the fastening and said finger to normally hold 80 both in their operative positions.

8. The combination with a base-plate and a catch-plate having a lug, of a hasp pivotally attached to the base-plate at one end and adapted to engage the lug on the catch-plate, 85 a holding-finger pivotally attached to the base-plate at one end and upwardly curved at its opposite end to receive an article beneath the same and springs engaging said hasp and finger to normally hold the same in engagement with the catch-plate and base-plate, respectively. 90

9. The combination with a base-plate having upwardly-extending walls and a catch-plate provided with an upwardly-extending 95 lug, of a hasp pivoted upon said walls at one end and adapted to engage the lug on the catch-plate, a holding-finger pivoted at one end on said walls and upwardly curved at its 100 opposite end to hold an article between it and the base-plate, lugs extending from the pivoted ends of said hasp and finger, and springs exerting a force upon said lugs to hold the hasp engaged with its catch-plate and the finger down upon the base-plate. 105

10. The combination of a casing having openings in its side walls, a catch-plate having an upwardly-extending lug, a hasp having a cross-bar at one end extending through the openings in the casing, a holding-finger having a cross-bar at one end extending through the openings in the casing and upwardly curved near its opposite end, a lug on each cross-bar within the casing adjacent to one wall of the casing, and a spring adjacent to each wall and each engaging the lug at its side of the casing. 110

11. The combination of a casing having openings in its side walls and a key-opening in its top, a catch-plate having a lug, a loop-shaped hasp having its cross-bar at one end journaled in the openings in the sides of the casing, a holding-finger formed with a loop at one end having a cross-bar journaled in the openings in the sides of the casing at a distance from the other cross-bar, a lug on each 115 120 125

cross-bar lying in the plane of the sides of the loops, a spring to engage each lug, a vertically-extending stud between the cross-bars adapted to be turned by a key, and arms on 5 said stud to extend over the cross-bars when the stud is turned by the key to lock the hasp and holding-finger.

In testimony whereof I affix my signature in presence of two witnesses.
